INVENTOR :

Benno Frederick Jancke,

By Attorneys,
Fraser Myrus & Manley.

UNITED STATES PATENT OFFICE.

BENNO FREDERICK JANCKE, OF NEW YORK, N. Y., ASSIGNOR TO SHELTON-JANCKE CORPORATION, OF NEW YORK, N. Y., A CORPORATION OF NEW JERSEY.

HEATER FOR HAIR WAVING.

Application filed December 28, 1923. Serial No. 683,202.

This invention relates to improvements in heaters for hair waving, and aims to provide improvements therein.

Heaters such as are generally used at present are objectionable in that they are too hot for handling with bare hands, and cause painful burns in cases of accident.

The aim and purpose of the present invention is to provide a heater which is so cool externally that it may be handled with bare hands, and which is not liable to cause burns like those heretofore generally used. The heater of this invention also requires to be supplied with a less amount of heat than those heretofore generally used.

An embodiment of the invention is illustrated in the accompanying drawing, of which,—

Figure 1 is a side elevation;

Fig. 2 is an end view;

Fig. 3 is a vertical sectional view, and

Fig. 4 is a horizontal section.

Referring to said drawing, numeral 10 designates a hollow tube or double-walled chamber, preferably of heat resistant glass, the interior of which is exhausted, as in the Dewar vacuum bottles. The inner faces of the tube are preferably made reflective, as by being silvered, as indicated at 13, so as to reflect heat rays.

A heating means 15 is placed inside of the tube 10, as shown in Fig. 3, and the heating means 15 is preferably an electrical resistance in the form of a coil of wire 17. The wire is preferably bare and spaced apart in the coils. A sheet of mica 19 is conveniently placed between the coil 17 and the inner walls of the tube 10, and a metal sleeve 21 is preferably placed inside of the coil 17, so as to enclose the coil between the hollow tube 10 and the metal sleeve 21. The ends of the sleeve are preferably turned in against the hollow tube 10, as indicated at 23, 24, so as to tightly enclose said coil 17. A sheet of mica, or the like, is preferably placed between the coil 17 and the sleeve 21. The tube 10 is conveniently formed with an inner annular rib 25, at or near one end,

which serves as a shoulder against which the coil 17 and sleeve 21 may rest. 50

The hollow tube 10 may have a sealing tube 27 projecting therefrom at one end, and the lead wires 31, 32 may be fastened to this sealing tube 27, as indicated at 34.

A number of these heaters for waving a 55 head of hair, may be used, as is usual.

The exhausted tube 10 prevents the transmission of heat through the tube by convection, and the reflecting surfaces 13 turn back the radiant heat waves. The heat of the resistance coil 17 is therefore confined inward of the tube 10, so that the exterior of the tube 10 is always comfortable for handling with bare hands, very much facilitating the dressing of the hair, the applying of the 60 heaters, their adjustment during the period of heating, and the rescue of the subject in case of some accident which produces discomfort. Moreover, by reason of the less radiation of heat, in the case of an electric 70 heater, less current is necessary for producing and maintaining a desired temperature, which reduction of current consumption is important in this class of heaters.

The invention may receive other embodiments than that herein specifically illustrated and described. 75

I claim as my invention:

1. A heater for hair curling comprising a tubular part adapted to receive a strand of hair within it, an electric heating element, and an exterior double-walled exhausted chamber forming a heat non-conductor to prevent outward radiation of heat and keep the exterior of the device cool so that it may 80 be readily handled. 85

2. A heater for hair curling comprising an inner tube, an electric heating element around said tube, and an exterior double-walled exhausted chamber of sealed glass 90 enclosing said heating element.

3. A heater according to claim 1, with reflecting surfaces exterior to the heating element for reflecting inward the radiant heat.

4. A heater for hair curling, comprising 95 an electric heating element adapted to en-

close a coiled strand of hair, and an exhausted double-walled tubular chamber externally surrounding said element, said chamber having a sealing tube to which the wires leading to said heating element may be fastened.

5. A heater for hair curling, comprising an electric heating element adapted to enclose a coiled strand of hair, and an exhaust-

In witness whereof, I have hereunto signed my name.

BENNO FREDERICK JANCKE.
